J. E. RODGERS.

FUEL OIL BURNER.

APPLICATION FILED NOV. 1, 1920.

Patented Oct. 4, 1921.

INVENTOR
JOHN E. RODGERS.

BY *Fetherstonhaugh & Co.* MARY.

UNITED STATES PATENT OFFICE.

JOHN EDWARD RODGERS, OF IMPEROYAL, NOVA SCOTIA, CANADA.

FUEL-OIL BURNER.

1,392,450.

Specification of Letters Patent.

Patented Oct. 4, 1921.

Application filed November 1, 1920. Serial No. 421,055.

To all whom it may concern:

Be it known that I, JOHN EDWARD RODGERS, a subject of the King of Great Britain, a resident of the town of Imperoyal, Province of Nova Scotia, Dominion of Canada, have invented certain new and useful Improvements in Fuel-Oil Burners, of which the following is a specification.

This invention relates to improvements in fuel oil burners, and the objects of the invention are to provide a simple and effective device by which fuel may be atomized and with a maximum economy.

Further objects are to improve and simplify the construction of the device to better adapt it to perform the functions required of it, and it consists essentially of the improved construction hereinafter described in detail in the following specification and accompanying drawings forming part of the same.

In the drawings:

Figure 1 is a sectional view through an embodiment of the invention.

Fig. 2 is a rear end view.

Fig. 3 is a front end view.

Fig. 4 is a plan view.

Like characters of reference indicate corresponding parts in all the figures.

Referring to the drawings; A represents the burner including a fuel nozzle D and a steam nozzle C both conveniently cast together in one piece.

The openings of the nozzles as seen, extending transversely across the front of the member A being elongated transversely, the nozzle C opens against a plane surface 10 which extends immediately above the opening in the nozzle D.

The nozzle C is provided with a controlling member D and the nozzle B with a controlling member E. These controlling members are adjustably held in position, the member D being held by a bolt 11 which extends through a slot 12 in the member D and has screw threaded engagement with suitable screw threaded perforations 13 in the member A.

The member E is adjustably held in position by two bolts 14 extending through slots 15 in the member E and engaging a suitable screw threaded perforation in the member A.

The controlling member E is in the form of a flat plate formed on the inner side with a channel 16 and formed on the top with a

channel 17, these channels being adapted to guard fuel and cause it to be distributed in the form of a fine film which is atomized by the steam distributing it over the surface end. 60

The lower edge of the controlling member D is formed with a suitable channel 18 which forms an opening through the steam which is distributed in a fine sheet of spray 65 and caused to commingle with the oil and atomize the same.

A suitable screw threaded neck 20 is provided on the rear forming an extension over the fuel nozzle and being adapted to be 70 connected to a suitable supply of fuel oil. The nozzle C connects with a similar neck 21 adapted to be connected to a supply of steam.

The burner may be used or connected to 75 any suitable supply of fuel oil and in any place where it is desired to generate heat, the principal use being a steam boiler in which the burner may be placed in the fire box. 80

In operating, the fuel oil is first forced with fuel nozzle under pressure and lighted. The steam is then forced with a steam nozzle and it will atomize the fuel oil and enable a high temperature to be obtained. 85

As many changes could be made in the above construction and many widely different embodiments of my invention within the scope of the claims, constructed without departing from the spirit or scope thereof, 90 it is intended that all matter contained in the accompanying specification and drawings shall be interpreted as illustrative and not in a limiting sense.

What I claim as my invention is:

1. A fuel oil burner comprising a fuel nozzle, a steam nozzle, each of the said nozzles having a suitable discharging port which said ports are adjacent to each other and being adapted to discharge in a plane 100 substantially at right angles to the ports, and independently adjustable controlling plates for each nozzle adapted to be adjusted in a plane transverse to the plane of discharge of the fuel. 105

2. The device as claimed in claim 1, in which the steam nozzle discharges against a plane surface and in which controlling plates are mounted adjustably on plane surfaces which extend at substantially right 110 angles to the first-mentioned plane surface.

3. A fuel oil burner comprising a nozzle

having a discharge port and a plane surface extending outwardly therefrom, a second nozzle having an inclined discharge port discharging at the end of the afore-
5 said plane surface, and adjustable controlling plates adapted to be adjusted across the discharge port of each nozzle.

4. A fuel oil burner comprising a fuel nozzle, a steam nozzle, the steam nozzle being adapted to discharge along a plane surface, a transversely adjustable controlling plate mounted across the end of the nozzle, the controlling plate extending across the

fuel nozzle having a channel in the face, the upper side of the controlling plate which 15 extends across the steam nozzle having a channel in the lower edge, the said nozzles being adapted to discharge the fuel and steam in thin sheets adapted to comingle and atomize.

In witness whereof I have hereunto set my hand in the presence of two witnesses.

JOHN EDWARD RODGERS.

Witnesses:

J. L. MACKINNON,
G. C. GRIFFIN.
